No. 737,318.

PATENTED AUG. 25, 1903.

M. J. BEBB & E. G. EATON.
CURTAIN DISPLAY APPARATUS.

APPLICATION FILED NOV. 28, 1902.

NO MODEL.

UNITED STATES PATENT OFFICE.

MAURICE J. BEBB, OF XENIA, AND EDWARD G. EATON, OF ATHENS, OHIO.

CURTAIN-DISPLAY APPARATUS.

SPECIFICATION forming part of Letters Patent No. 737,318, dated August 25, 1903.

Application filed November 28, 1902. Serial No. 132,987. (No model.)

To all whom it may concern:

Be it known that we, MAURICE J. BEBB, a resident of Xenia, in the county of Greene, and EDWARD G. EATON, a resident of Athens, 5 in the county of Athens, State of Ohio, citizens of the United States, have invented certain new and useful Improvements in Curtain-Display Apparatus, of which the following is a specification.

10 We have obtained Letters Patent of the United States No. 710,408 for a curtain-display rack which is so constructed as to support curtains or other fabrics and facilitate their display.

15 Our present invention has for its object to provide an improved attachment for such rack, its functions being to provide an improved support for the dust-curtains, which protect the display-curtains, and to provide 20 a bearing for the upper end of the rod or shaft upon which the arms for supporting the displaying-curtains are journaled.

The details of construction, arrangement, and combination of parts are as hereinafter 25 described, reference being had to the accompanying drawings, in which—

Figure 1 is a front elevation of our invention, one of the dust-curtains being drawn and one of the swinging arms for carrying 30 display-curtains being thrown outward. Fig. 2 is a section on line 2 2 of Fig. 1, showing a bottom plan view of the overhead board, which aids in protecting the display-curtains from dust and also supports the dust-curtains 35 proper. Fig. 3 is a perspective view of the support for the active members of the display-rack.

Referring to Fig. 1, 1 indicates a series of wire loops arranged in horizontal position 40 and constituting swinging arms from which display-curtains or other fabrics are to be hung. These arms 1 are suitably journaled upon a grooved rod or shaft 2 and are thus adapted to be swung horizontally. The said 45 rod or shaft 2 is journaled in a bracket 3 and in a combined foot and bracket 4. (See also Fig. 3.) The brackets 3 and 4 are provided with horizontal base-pieces 5, which are secured by means of screws to a vertical board 50 or plate 6, which is in turn secured permanently to a fixed support—say a wall. The

bracket 4 is provided with a socket in its under side to receive the upper end of the rod or shaft 2, and on its upper side it is provided with a triangular piece or flange 4^a, 55 (see Fig. 3,) which is ordinarily termed the “foot.” This foot is screwed to the under side of the overhead board 7. (See Figs. 1 and 2.) It is apparent that since the combined bracket and foot 4 and 4^a constitutes a rigid attachment of the vertical support 6, it will also serve as a means for supporting the board 7 in horizontal position. The board 7 is oblong and rounded at the corners, having thus close resemblance in both size and form to a board 60 mantel. Its rear edge rests in contact with the wall to which the vertical support 6 is secured. To its under side we apply two curved rods 8, the same being approximately right angular in form. Their inner or adjacent ends 65 lap past each other, as shown, and the dust-curtains 8^a being suspended from the respective rods by means of rings it is obvious that that the said curtains may be easily slid on the rods, so as to be opened as required to 70 entirely display curtains or fabrics suspended from the swinging arms 1 or to permit such dust-curtains to be drawn past each other, so as to inclose and protect the display-curtains. The board 7 thus serves not only to support 75 the dust-curtains, but protects the display-curtains from access of dust from above. We thus combine in one simple cheap apparatus means for supporting and displaying curtains and fabrics of various kinds and 80 also for holding them in small space when display is not required and for effectively protecting them from dust and light when inspection is not called for.

The rod 9 and spring 10, (shown in Fig. 90 1,) constituting an attachment of the arm 11, which is pendent from the bracket 3, constitute a means for supporting a curtain or fabric adapted to serve as a background against which lace curtains may be displayed 95 when duly suspended from the swinging arms 1. As represented in Fig. 1, one of the dust-curtains 8^a is pushed back or drawn to its farthest limit, and one of the pivoted arms 1 is shown thrown out to display a curtain suspended thereon and whose outline is indicated by dotted lines. 100

Having thus described our invention, what we claim as new, and desire to secure by Letters Patent, is—

1. The improved apparatus for protecting and displaying curtains and other fabrics, the same comprising an overhead board arranged horizontally and provided with rods whose inner ends extend past each other, dust-curtains suspended from said rods and adapted to lap in the manner described, a vertical rod and arms pivoted thereon for supporting display-curtains, said arms being adapted to fold beneath the overhead board, and a combined foot and bracket adapted to support the overhead board, and a lower bracket which, together with the upper bracket, constitutes bearings for the aforesaid vertical rod, substantially as shown and described.
2. The combination, with the overhead board serving as a dust-protector and provided with means for supporting dust-curtains, of a combined foot and bracket and a

lower bracket, a vertical support to which said brackets are secured, a vertical rod held in said brackets, and display-curtain frames journaled on the said rod, substantially as shown and described.

3. The combination, with an overhead support and rods secured thereto and adapted for support of dust-curtains, of the combined bracket and foot secured to the overhead support and a wall, a second bracket arranged below the first one, a vertical rod held in said brackets and swinging arms for display-curtains arranged substantially as shown and described.
